Patented July 25, 1922.

2 SHEETS—SHEET 2.

UNITED STATES PATENT OFFICE.

MARVIN H. JESTER, OF PHILADELPHIA, PENNSYLVANIA.

PLASTER-BOARD SUPPORT.

1,423,939.

Specification of Letters Patent.

Patented July 25, 1922.

Application filed February 2, 1920. Serial No. 355,866.

To all whom it may concern:

Be it known that I, MARVIN H. JESTER, a citizen of the United States, residing at Philadelphia, in the county of Philadelphia and State of Pennsylvania, have invented certain new and useful Improvements in Plaster-Board Supports, of which the following is a specification.

This invention relates in general to plaster board supports, and more particularly to supports by which sheets or blocks of plaster board may be attached to the concrete beams of a ceiling.

One of the primary objects of this invention is the provision of a support of this character which can be quickly and accurately placed in position before the concrete of the beam is poured and which, when positioned, can be quickly and easily engaged with the plaster board as it is applied and will securely and firmly support the plaster board in position.

Another object of the invention is the provision of a support which shall consist of a series of individual clip members arranged in the required spaced relation and fastened together so that the whole series can be simultaneously positioned and when positioned, will be disposed in parallel relation and in the proper position.

A further object of my invention is to provide a support of this character, which may be closely associated with the concrete reinforcing rods of the structure so that the supports will occupy but little space, and also to provide a support which can be cheaply manufactured, quickly placed in position, and which will be strong and durable in use.

Other objects and many of the advantages of my invention will be readily appreciated by those skilled in the art as the same becomes better understood, by reference to the following description when considered in connection with the accompanying drawings:

Referring to the drawings—

Fig. 1 is a perspective of one of the clip members of my invention;

Fig. 2 is a transverse sectional view through a ceiling beam equipped with a support embodying my invention;

Fig. 3 is a perspective view of one of the connecting wire elements;

Fig. 4 is a fragmentary view looking at a

plaster board ceiling supported by my improved support;

Fig. 5 is a fragmentary view looking upwardly at the reinforcing rods of a beam with my support in position, the concrete beneath the rods being removed to more clearly illustrate the application of my invention;

Fig. 6 is a transverse sectional view on the line 6—6 of Figs. 2 and 4;

Fig. 7 is a perspective view of a modified form of my invention, and

Fig. 8 is a detail of the modified connecting link.

From an inspection of the drawings and more particularly Fig. 1 thereof, it will be observed that my invention comprises essentially a series of clip members, one of which is shown in Fig. 1. These members are made of sheet metal of suitable weight, which is bent into substantially inverted channel-shaped form as shown, the channel shape body portion 7 being of a length slightly less than the width of the ceiling beam in which it is to be imbedded. Between its ends, this channel shaped member is cut away to provide two transversely disposed seats—8 and 9, adapted to accommodate a pair of parallel concrete reinforcing rods such as are indicated at 11 and 12 in Figs. 2 and 4.

Each clip member is formed to provide laterally extending flanges 13 and 14 respectively of appreciable width, these flanges being each severed throughout substantially one half of its length from the body portion of the member as indicated at 15, so as to leave a portion of the flange free to be bent downwardly upon itself to form a plaster board supporting clip. The position of the flanges when bent into plaster board supporting position is shown in Fig. 2, wherein the free end of the flange 13 is indicated by reference character 16 and the free end of the flange 14 is indicated by reference character 17. It should be noted that these flanges are severed at opposite ends of the body portion so that they bend downwardly in opposite directions to engage the opposed edges of plaster boards indicated in Fig. 2 by 18 and 19 respectively.

Before these members are placed in position, a series of them are connected together so that they form in effect, a string or chain of clip members connected together and held

in parallelism in the proper spaced relation. For the purpose of connecting a series of these clip members together, I employ a series of wire loops 21, one of which is shown in Fig. 3. These loops are slightly narrower than the overall length of the clip members and the ends of each clip member are provided with inwardly extending slots 22 to accommodate the sides of these loops. 5 Each loop is adapted to embrace two clip members, the ends 23 of the loop being engaged with the longitudinal side walls of the clip members as shown in Fig. 5, in which only one clip member 7 is shown, but 10 the position of the overlapping wire loops being indicated, from which it will be apparent how a clip member is embraced by and held between two of these loops. The 15 ends of the wire loops will, of course, prevent the clips from separating, but to insure that the members will be retained in the proper spaced relation and will not move toward each other, I prefer to bend the longitudinal members of the wire connecting 20 elements inwardly, as indicated at 24 between the side walls of each clip member as best shown in Figs. 3 and 5, so that these inwardly bent portions prevent movement of the clip members longitudinally of the 25 wire connecting links or elements and insure that these members will be maintained in parallelism and in the proper spaced relation. One of the members embraced by two 30 of the wire connecting elements 21 is clearly 35 shown in Fig. 6.

In the use of my improved support, a series of these clip members is connected together by wire connecting elements in the manner described, to form a chain, which 40 is then placed in position in the body of the mould into which the concrete for the ceiling beam is to be poured. This mould is then placed in position around and beneath the concrete reinforcing rods with the 45 clip members disposed beneath the rods and in engagement therewith, the seats 8 and 9 formed in the members, permitting these members to be closely associated with the rods so that they extend upwardly a considerable 50 distance into the body of the beam insuring a firm anchorage, but at the same time it will be observed that they occupy but little space beneath the reinforcing rods so that the depth of the beam need not be 55 increased over the normal.

After the series of clip members have been positioned in the mould as explained, the concrete is poured and while in its semi-liquid condition, it flows into the ends 60 of the clip members and into the seat openings around the rods, which are made larger than the rods to facilitate the entrance of the concrete, with the result that the concrete completely fills the interior of the 65 clip elements, as shown in Fig. 6, thereby

firmly bonding and securely anchoring the elements into the body of the beam, which is indicated in Figs. 2 and 6 by reference character 25.

After the beam has set and the moulds 70 have been removed, the flanges 13 and 14 of each clip member lie substantially flush with the bottom of the beam. In order to apply the plaster board which forms the ceiling, it is only necessary to bend the free ends of each 75 flange downwardly and back upon itself, as shown in Figs. 2 and 4, to form the fastening clips by which the plaster board is supported. This bending of the flanges may be readily effected with a hammer or other 80 preferred tool, and it can be done very quickly. When the clips are bent over beneath the end face of the plaster board, they serve to firmly and securely support 85 it in position and since the clips proper are relatively thin, a thin coat of plaster over the whole surface is sufficient to completely cover and hide the clips from view.

In some instances, as a matter of additional security, it may be desirable to nail 90 the clips to the plaster board and in order that this may be done when desirable, I provide the free portion of the flanges which form the clips proper with a hole 26 near the free end thereof, while the opposite fixed 95 end of the flange is beveled off as indicated at 27, so that when the free end is bent downwardly and back upon the fixed end, the hole 26 is disposed longitudinally beyond the beveled end 27 so that a nail driven upwardly through the hole 26 and through the 100 plaster board will not engage the fixed portion of the flange, but may pass upwardly through the plaster board beyond the end of the flange.

In Figs. 7 and 8 I have illustrated a modified form of connecting link which may be used in lieu of the loop links 21 previously described. In this instance, the link consists of a longitudinal portion 28 110 provided at one end with an eye 29 and at its other end with a transversely disposed portion 31 terminating in a reversely bent hook 32. A series of these links may be united by inserting the transverse hooked 115 portion 31 of one link through the eye 29 of the adjoining link, whereupon the hooked end 32 is engaged with a clip member 7, as shown in Fig. 7, thus connecting a series of these members together so as to maintain 120 them in definite spaced relation.

It is believed that the construction, mode of operation and many of the advantages of this invention will be understood from the foregoing without further description, 125 and it should be obvious that various changes in the structural details illustrated and described may be resorted to without departing from the spirit of the invention, as defined in the following claims. 130

I claim:

1. A plaster board support comprising a series of clip members arranged in spaced relation, each provided with plaster board supporting clips, and a series of wire loops, each embracing two of said members to maintain the members in definite spaced relation. 45
2. A plaster board support comprising a plurality of members adapted to be disposed in parallel spaced relation, the ends of said members being provided with longitudinally extending slots, and means embracing said members and engaged in said slots whereby the members are maintained in definite spaced relation. 50
3. A plaster board support comprising a plurality of channel-shaped members, provided with slots, and wire loops engaging said members and disposed in said slots whereby the members are connected together and maintained in parallelism in definite spaced relation. 55
4. A plaster board fastener comprising a channel-shaped member, provided with a plurality of transversely disposed seats, and having longitudinal flanges folded upon themselves for supporting plaster board elements. 60
5. A plaster board support, comprising a channel-shaped member provided with laterally extending flanges, said flanges being free from the walls of said member throughout a portion of their length permitting said free portions to be folded upon the remaining portions into plaster board supporting position. 65
6. A plaster board support, comprising an elongated member provided with a laterally extending flange having one portion attached to the member and another portion adjacent said member, free therefrom, said free portion being adapted to be folded longitudinally of the member upon the attached portion into plaster board supporting position. 70
7. A plaster board support comprising a channel-shaped member, provided with laterally extending flanges, the flanges at opposite sides of the body portion of the member being connected throughout a portion of their length only with said body portion so as to leave a portion of each flange free to be bent about an axis extending transversely of said members into engagement with a plaster board for the purpose of supporting same. 75
8. A plaster board support comprising a channel-shaped member, provided with oppositely disposed laterally projecting flanges, each separated throughout a portion of its length from the body portion of said member to permit the free ends of said flanges to be bent in opposite directions into plaster board supporting clips extending longitudinally of said members. 80
9. A plaster board support comprising an inverted channel shaped member, provided with oppositely disposed flanges separated throughout a portion of their length from the body portion of said member, said body portion being also provided with slots at each end to accommodate connecting members and with transverse seats to accommodate concrete reinforcing rods. 85
10. A plaster board support comprising a channel-shaped member, provided with plaster board supporting clips, and a wire member adapted to engage one side and an end of said member, said wire member being engaged in slots formed in the side walls of said channel-shaped member to lock the same against displacement from said member. 90

MARVIN H. JESTER.
